FACSIMILE SCANNING SYSTEM

William G. H. Finch, Newtown, Conn.

Original application June 26, 1937, Serial No. 150,489. Divided and this application May 16, 1940, Serial No. 335,473

2 Claims. (Cl. 64—27)

This invention relates to facsimile systems and more particularly relates to novel apparatus for providing smooth scanning at the record sheet.

In a facsimile transmitter or receiver the record sheet is scanned line by line at a predetermined rate. In commercial operation rate of scanning generally ranges between 50 and 100 lines a minute. The operation of the scanner is by means of a motor with gear-down mechanism between the motor and the scanner. It has been found that gearing arrangements for driving the scanner mechanism cannot satisfactorily provide smooth operation of the scanner, particularly scanners of start-stop type receivers. The vibrations set up in the drum due to the starting and stopping thereof, in conjunction with gearing rattle between the continuously rotating motor and the drum, cause striations to appear on the recorded picture. Striations traceable to the actual gear arrangements appear as alternate dark and light parallel streaks transverse to the scanning direction.

I have found that by providing a mechanical filter arrangement at the scanner mechanism, striations due to the spurious vibrations in the scanning system are substantially eliminated. In a preferred form of my invention, I couple the scanner to a driving plate with a pin and provide a flexible connection between the pin and the driving plate. By properly proportioning the elasticity of the flexible connection and the rotative inertia of the scanner mechanism cooperating therewith, the scanner will be operated in a smooth manner and the vibrations causing striations on the record sheet will be practically eliminated.

Accordingly, it is an object of my present invention to provide novel method of and means for driving a facsimile scanner mechanism.

A further object of my present invention is to provide novel method of and apparatus for coupling a scanner mechanism to a driving member for smoothing out fluctuations in the scanner movement.

A further object of my present invention is to provide a novel method of and means for operating a rotating drum scanner of a facsimile system.

These and further objects of my present invention will become apparent in the following description of preferred forms for carrying out my invention taken in connection with the drawing, in which:

Figure 1 is a plan view of a facsimile recording unit embodying one form of my invention.

Figure 2 corresponds to the view taken along 2—2 of Figure 1.

Figure 3 is the cross-sectional view taken along 3—3 of Figure 1 through the mechanical driving connection to the drum.

Figure 1 is a plan view of a preferred form of a picture recorder in conjunction with which my invention is employed. It is to be understood that different types of recording mechanisms may equally well be used with my invention. The illustrated facsimile recorder is of the general type described in my Patent No. 2,047,863, which issued on July 14, 1936, entitled "Telecommunications system," and specifically of the form disclosed in my co-pending application Serial No. 84,426, filed June 10, 1936 entitled "Telepicture scanning systems."

The record sheet 10 is mounted upon a rotatable drum 11 by means of the sheet fastening members 12. The rollers 13 are used to facilitate smooth mounting of sheet upon the drum. Drum 11 is removably mounted between the pointed spindle 14 of the tailstock 15 and a shaft located within the housing 16 which is coupled to the drive motor 17 energized by a local power source through connection leads 18.

The motor 17 is driven near the predetermined synchronous speed and synchronizing mechanism (not shown) is used to maintain the drum 11 in exact phase and synchronous relation with the corresponding transmitter drum by means of cyclic synchronizing signals. The drum 11 is preferably operated on the start-stop principle in response to the synchronizing signals which operate a clutch located within housing 16.

In the preferred mechanism, drum 11 is operated at 100 revolutions a minute, while motor 17 operates at 1800 revolutions a minute, requiring an 18:1 speed reduction ratio between the motor and the drum.

The electro-optical recording apparatus is contained within the movable carriage 20 and is operated in a path parallel to the axis of the drum 11 by means of a feed-screw 21 rotated in a predetermined speed ratio with respect to the drum 11 by means of reduction gearing located within the housing 22. The scanner carriage 20 is guided in the parallel tracks 23—24 and is secured to the feed-screw 21 by operating the cam lever 25 in a manner fully disclosed in my patent and application referred to above. The received facsimile signals are caused to produce a light beam 26 varying in accordance with the shading of the original picture being transmitted 55 in order that the resulting picture traced upon

the recording sheet 10 will correspond thereto. The picture drum 11 is coupled to the drive plate 27 by means of a pin 28 attached to the left flange 30 of the drum 11. Figures 2 and 3 illustrate details of the mechanical filter coupling between the drive plate 27 and the drum 11. Pin 28 is preferably encased by a rubber layer 31 and is fitted between two parallel leaf spring members 32—32 set into a recess 28 in the drive plate 27.

The drive plate 27 is operated directly from the synchronizing clutch member (not shown) and is supported on the housing 16 by a roller bearing 33. A spindle 34 projects through the center of the drive plate 27 for properly supporting the drum 11 in its axis of rotation. The rotation of drive plate 27 applies a rotative torque directly to the pin 28 through the leaf spring members 32 to rotate drum 11.

The flexibility of the springs 32 is properly proportioned in conjunction with the rotative mass or inertia of the drum 11 to smooth out the spurious vibrations thereof. I have found that a drum having a relatively large rotative inertia is preferable, and have illustrated a cylinder 35 of lead or other heavy material attached to the flange 30 to increase the inertia or mass of the normally hollow drum 11.

It is important to have the leaf springs 32 adjusted accurately tangent to the pin 28 at its outer rubber surface covering 31 as illustrated in Figure 2. I have provided a simple method for maintaining this adjustment by the tapered pin 36 set into a slot 37 in the drive plate 27 centrally between the spring members 32. The tapered pin is forced between the sides of the narrow slot 37 until the proper operation of the leaf springs 32 is attained. This separation corresponds to the tangential alignment of the springs

32 and the rubber covering 31. The flexibility inherent in the springs 32 and the cylinder of rubber 31 acting co-jointly with the rotational mass of cylinder 11 has been found to practically eliminate the vibrational tendencies of the drum causing dark and light alternate striations on the record sheet thereby greatly enhancing the quality of the reproduction.

Although I have illustrated preferred forms 10 for carrying out my invention it is to be understood that modifications thereof are feasible and accordingly I do not intend to be limited thereby except as set forth in the following claims.

This application is a division of my Patent No. 15 2,204,271, issued June 11, 1940 for Facsimile scanning system.

I claim:

1. A mechanical filter arrangement between a driving means and driven means comprising a drive plate operable by said driving means, said drive plate containing two leaf springs having opposed surface portions, a tapered peg set in a slot of said drive plate extending between said springs for adjusting the amount of separation of said springs and a pin attached to said driven means and arranged to coact with said leaf springs between the opposed surface portions thereof.

2. A mechanical filter arrangement between a driving means and driven means comprising a drive plate operable by said driving means, said drive plate containing two opposed springs, a tapered peg set in a slot of said drive plate extending between said springs for adjusting the amount of separation of said springs and a pin attached to said driven means and arranged to coact with and register between said opposed springs.

WILLIAM G. H. FINCH.
